3,075,593 DRILL BIT

Robert H. Holsing, Canton, Ohio, assignor to The Timken Roller Bearing Company, Canton, Ohio, a corporation of Ohio

Filed Nov. 18, 1959, Ser. No. 853,934
3 Claims. (Cl. 175—383)

The present invention relates to drill bits of the type in which a plurality of cutting bits are removably retained on the face of a bit holder.

It is an object of the present invention to provide a drill bit comprising a bit holder and a plurality of cutting bits.

Another object of the present invention is to provide a drill bit wherein the cutting bits are retained in the bit holder by a tapered friction lock. Still another object is to provide a cluster bit wherein the cutting bits have engaged portions which prevent relative movement therebetween.

Another object of the present invention is to provide a cluster bit in which the cutting bits can be removed from the bit holder by forcing a tapered wedge under the heel of the shank portion of the cutting bit.

A further object is to provide a cluster bit wherein the cutting bits are grouped radially. Another object is to provide a cluster bit arrangement having a pilot bit mounted forward of the other cutting bits.

The cluster bit of the present invention has the outstanding advantage over present bits that each individual cutting bit can be rotated on its own axis to obtain a new gauge cutting edge without affecting any other bit in the group.

Another advantage of the present invention is that the individual cutting bits are provided with abutting shoulders which keep them from turning when the drill is used, thus keeping the gauge diameter of the hole more accurate.

Another advantage is the interchangeability of reusing usable parts from a damaged or worn-out bit assembly in another bit assembly for complete use of the parts.

Still another advantage of the present invention is that the tapered friction lock retains the cutting bits in the bit holder without their bottoming on the bit holder, either at the small end of the bit or at the forward face of the bit holder. A tapered friction lock combined with a positive shoulder or bottom stop becomes loose during the continual hammering to which the bit is subjected in use.

These and other objects and advantages will become apparent hereinafter.

The present invention comprises a cluster bit including a plurality of cutting bits retained in a bit holder and further consists in the parts and combinations and arrangements of parts hereinafter described and claimed.

In the accompanying drawings, which form part of the specification and wherein like symbols refer to like parts wherever they occur,

FIG. 1 is a partially broken side elevational view of a cluster bit embodying the preferred form of the present invention,

FIG. 2 is an end elevational view of the cluster bit shown in FIG. 1,

FIG. 3 is a side elevational view of a modification of the present invention,

FIG. 4 is an end elevational view of the modification shown in FIG. 3,

FIG. 5 is a side elevational view of a modification of the present invention,

FIG. 6 is a side elevational view of another modification of the present invention,

2

FIG. 7 is an end elevational view of the modification of the present invention shown in FIG. 6,

FIG. 8 is a side elevational view of another modification of the present invention, and

FIG. 9 is an end elevational view of the modification shown in FIG. 8.

FIG. 1 shows a drill bit 10 including a bit holder 11 having a shank 12 adapted to engage a drill rod 13. The bit holder 11 has a front face 14 which is provided with tapered sockets 15. Each socket 15 tapers inwardly from an open end at the forward face 14 of the bit holder 11 to a base wall 17 which is smaller than the open end.

Each of the cutting bits 18 comprises a head portion 19 including a cutting face 20, hardened cutting inserts 21, and flattened sides 22 terminating in a shoulder 23 opposed to the cutting face 20, and a tapered shank portion 24 ending in a small butt end 26. The tapered shank portion 24 forms a friction lock with the correspondingly tapered socket 15 in the bit holder 11.

When the cluster bit 10 is in use, the flattened sides 22 of the cutting bit 18 abut against corresponding sides 22 on other bits 18, thus preventing relative rotation between the bits 18. The shoulder 23 of the bit head 19 does not touch the front face 14 of the bit holder 11, and the small end 26 of the tapered shank 24 does not engage the base wall 17 of the bit socket 15. The tapered friction lock maintains an engaged relation even during heavy use, whereas bits utilizing a tapered friction lock combined with a positive shoulder or bottom stop become loose in continued use.

The bit holder 11 is provided with openings 30 communicating with the tapered sockets 15. A drift pin 31 having a tapered flattened shoulder 32 is inserted into the opening 30 to loosen the cutting bits 18. The shoulder 32 of the drift pin 31 engages the small end 26 of the cutting bit shank 24, and as the pin 31 is forced further into the opening 30, it forces the cutting bit 18 outward, unlocking it from the bit holder 11. In place of the drift pin 31, the cutting bits 18 can be removed by the application of fluid or air pressure to the small end or bottom area 26 of the bit 18. The bits 18 also can be removed by forcing a tapered wedge between the small bit shoulder 23 and the holder face 14.

The bit holder 11 is also provided with a passage 36 opening on the face 14 whereby fluid or air can be forced into the cutting area to carry the rock chips away from the cutting area.

It is intended that either carbide insert bits or all steel bits can be used in this construction. Either single edge bits commonly known as chisel bits or multiple edge bits are suitable for use in the present invention.

The outer periphery of the cutting face 20 is defined by the outermost edges of the hardened cutting inserts 21. The diameter of the cutting face 20 must be greater than the diameter of the bit holder 11 to drill a clear hole which will hold the bit holder 11.

The small cutting bits 18 must be grouped radially in the bit holder 11 rather than in a single or double line. Radially grouped bits provide more speed when drilling because of the better coverage, and increase the life of the bit. The large number of cutting edges provided by the cluster bit construction of the present invention also adds to the life of the bit and to the speed of drilling. The present cluster bit provides more uniformly smaller chips when drilling, and these chips are more easily moved from the hole than large uneven chips. When the portion of a bit insert that defines the gauge diameter of the hole becomes worn, it is not necessary to discard the bit, since it can merely be turned a quarter turn and a new insert is presented to the gauge diameter. This is of considerable importance, since it increases the life of

the bit at least fourfold, besides giving a more constant gauge diameter and a more constant degree of sharpness to the cutting face.

If desired, the bit holder 11 can be made of a special material and heat treated to stand excessive hammering blows, while the bits 18 can be made from material suitable for brazing or otherwise attaching the cutting insert 21.

FIGS. 3 and 4 show a modification of the present invention wherein a pilot or lead bit 49 extends beyond the cutting area defined by the cutting faces 20 of the cutting bits 18. The outer periphery of the cutting area 20 is determined by the edge of the hardened inserts 21 outermost from the center of the bit holder 11. This arrangement of cutting bits has considerable advantage to certain types of soil and rock.

FIG. 5 shows still another modification of this invention wherein more than four cutting bits 18 are provided. This arrangement is adapted to have abutting shoulders and a pilot bit, if desired. One of the advantages of this construction is that abrasive resistant bits 18a can be used on the outer edges of the bit holder, and shock resistant bits 18b on the inside cluster.

A modification of the present invention shown in FIGS. 6 and 7 provides the cutting faces of the insert bits in the same plane, but utilizes chisel bits 41. The outer periphery of the cutting area 20 is defined by the edges of the hardened inserts 42 outermost from the center of the bit holder 11.

In a further modification shown in FIGS. 8 and 9, the insert bits 18 are set in the bit holder 11 at an angle. The center bit 43 is a pilot or lead bit similar to the construction shown in FIGS. 3 and 4. This type construction has certain advantages in some drilling situations.

Thus, it is apparent that there has been provided a novel drill bit including a bit holder retaining cutting bits having abutting shoulders to restrain rotation between the cutting bits, and a tapered friction lock retaining the cutting bits in the bit holder, which fulfills all of the objects and advantages sought therefor.

This invention is intended to cover all changes and modifications of the examples of the invention herein chosen for purposes of disclosure which do not constitute departures from the spirit and scope of the invention.

What is claimed is:

1. A drill bit comprising a drill bit holder provided with a plurality of open ended tapered sockets, a plurality of cutting bits comprising head portions having a plurality of equally spaced slots therein, and tapered shank portions terminating in butt ends constructed and arranged to engage the tapered sockets in the bit holder thereby forming the only contact between said bits and said holder, and cutter inserts retained in the slots of the bits, the outer peripheral edges of the cutter inserts defining the gauge diameter of a cutting area, said bits being constructed and arranged to tighten the connection between the shanks and the sockets during drilling, said bits being rotatable when disengaged from the sockets to present new distinct cutting edges to the gauge diameter of the cutting area before being reground, said number of new cutting edges corresponding to the number of slots and inserts of the cutting bits.

2. A drill bit comprising a drill bit holder provided with four open ended tapered sockets and angularly in-

clined passageways connecting the bases of said sockets with an outer side wall of said holder, the centerline of said sockets being parallel to the centerline of said bit holder, each of said passageways being equally angularly related to the bases of said sockets, four cutting bits comprising head portions each provided with four equally spaced slots therein, each of said bits including side walls having substantially equally spaced flattened areas thereon, and tapered shank portions terminating in butt ends constructed and arranged to engage the tapered sockets in the bit holder thereby forming the only contact between said bits and said holder, and cutter inserts retained in the slots of the bits defining a cutting area, said bits being constructed and arranged to tighten the connection between the shanks and the sockets during drilling and removable from the sockets by a force applied through the angularly inclined bit holder passageways against substantially the entire butt end of the bits, each of said cutting bits being retained in a predetermined fixed position in the bit holder through the engagement of a flattened side with a flattened side on an adjacent bit, said cutting bits being rotatable when disengaged from the sockets to present four distinct cutting edges to the gauge diameter of the cutting area before being reground.

3. A drill bit comprising a drill bit holder provided with four open ended tapered sockets, four cutting bits comprising head portions each provided with four equally spaced slots therein, each of said bits including side walls having substantially equally spaced flattened areas thereon, and tapered shank portions terminating in butt ends constructed and arranged to engage the tapered sockets in the bit holder thereby forming the only contact between said bits and said holder, and cutter inserts retained in the slots of the bits, the outer peripheral edges of said cutting inserts defining the gauge diameter of a cutting area, said bits being constructed and arranged to tighten the connection between the shanks and the sockets during drilling, each of said cutting bits being retained in a predetermined fixed position in the bit holder through the engagement of a flattened side with a flattened side on an adjacent bit, said cutting bits being rotatable when disengaged from the sockets to present four distinct cutting edges to the gauge diameter of the cutting area before being reground.
